THEODORE P. BROWN, OF WORCESTER, MASSACHUSETTS, ASSIGNOR, BY MESNE ASSIGNMENTS, TO SIMPLEX PLAYER ACTION CO., OF WORCESTER, MASSACHUSETTS.

PNEUMATIC PLAYER MECHANISM FOR MUSICAL INSTRUMENTS.

Application filed September 5, 1923. Serial No. 661,092.

My invention relates to pneumatic player mechanisms for musical instruments and has for its object to provide an improved construction of the bellows and pneumatic mechanism for actuating the player action, whereby the operation of the instrument is greatly improved.

When operating pneumatic player pianos of the type covered by the present invention, it is of the utmost importance that the bellows device which controls the operation of the player action be adapted to readily respond to the will of the operator, so as to produce the great range of pressure intensities required in order to play the instrument with the proper expression. It has been found that when the air reservoir or bellows is completely collapsed by the operation of the pump, the suction produced becomes very great, and that it is then very difficult for the operator to move the foot treadles which operate the pump. Obviously, with such a condition, it is impossible for the operator to produce the variations of pressure so necessary for playing with expression, without exerting undue effort in moving the foot treadles.

According to the present invention I provide an improved bellows device which is so constructed that as the reservoir collapses, the resistance offered to the movement of the foot treadles by the operator does not exhibit any marked increase, so that the operator is able to maintain at all times a complete control over the pressure, without unduly exerting himself. My invention further contemplates an improved construction of the pneumatic mechanism controlling the player action, the individual pneumatics being constructed as units easily removed from the instrument, and the entire pneumatic mechanism being adapted to be readily removed from the piano without disturbing the adjustments of the same. The above and other advantageous features of my invention will hereinafter more fully appear, reference being had to the accompanying drawings in which

Fig. 1 is a view, partially in section and partially in side elevation, of a player piano embodying my invention.

Fig. 2 is a view, showing on an enlarged scale, the bellows device shown in Fig. 1, one of the feeders being in section.

Fig. 3 is a view in perspective of the bellows device shown in Fig. 2.

Fig. 4 is a view, on an enlarged scale, of a portion of the pneumatic mechanism shown in Fig. 1.

Fig. 5 is a perspective view of one of the pneumatic units shown in Fig. 4.

Fig. 6 is a sectional view along the line 6—6 of Fig. 5.

Fig. 7 is a plan view of the diaphragm block of the pneumatic unit shown in Fig. 6.

Fig. 8 is an enlarged sectional view of the valve of the unit shown in Fig. 6.

Fig. 9 is a plan view of the guide for the valve shown in Fig. 8.

Like reference characters refer to like parts in the different figures.

Referring first to Figs. 1, 2 and 3, the bottom board of the piano is indicated at 1 and carries a pair of blocks 2 for supporting the air pump and reservoir. The air pump consists of a pair of feeders, each of which comprises a stationary leaf 3 and a movable leaf 4 connected by a suitable collapsible web 5, as best shown in Fig. 3. The movable leaf 4 is normally held in a collapsed position against the stationary leaf 3 by means of a spring 6 mounted on the outside of the feeder. The spring 6 consists of oppositely curved arms 7, which are adapted to engage lugs 8 provided on the leaves 3 and 4 respectively, so that the spring 6 is adapted to be readily removed from the feeder for the purpose of adjusting or replacing the same.

The movable leaf 4 of each feeder is connected to a foot treadle 9 by means of a link 10, and the treadles 9 are mounted for pivotal movement on a cross bar 11. As best shown in Fig. 3, the cross bar 11 is U-shaped in form and its ends are pivotally mounted in sockets 12 carried by the blocks 2. The cross bar 11 is adapted to be supported above the level of the floor by means of downwardly extending feet 13 which are adapted to be secured in position on the bar 11 by set screws 14. By means of the set screws 14, the feet 13 may be secured in different angular positions on the bar 11, so as to compensate for variations in the distance between the bottom board 1 of the piano and the floor on which the piano rests.

When the cross bar 11 is supported above the floor in front of the piano, as shown in

Fig. 1, it is obvious that the treadles 9 may be operated by foot pressure to cause the movable leaves 4 of the feeders to be moved back and forth to exhaust air from the collapsible bellows, or reservoir, to which the feeders are connected. The reservoir consists of a stationary leaf 15 and a movable leaf 16 connected by a collapsible web 17. The movable leaf 16 is normally held away from the stationary leaf 15 by means of springs 18 carried at the ends of the reservoir. Each spring 18 consists of divergent curved arms 19, the ends of which are in engagement with lugs 20 carried by the leaves 15 and 16 respectively, and the springs 18 may be readily removed from the reservoir for adjustment and replacement. The movable leaf 16 of the reservoir is formed of a number of separate laminations 16^a, so that the leaf possesses a certain amount of inherent resiliency, the advantage of which will be hereinafter referred to with reference to the operation of the pump and reservoir, as will now be described.

When the operator pushes down a treadle 9, the corresponding feeder is expanded, due to the movement of the leaf 4, and the atmospheric pressure on the outside of the feeder serves to hold a valve 21 in position to close the ports 22 in the leaf 4. The expansion of the feeder is adapted to exhaust air from the reservoir through a port 23 and a valve 24 which opens to suction. As soon as the operator releases a treadle 9, the action of the corresponding feeder spring 6 returns the movable leaf 4 to its collapsed position, whereupon the valve 21 opens to release the air through the ports 22 while the valve 24 closes to lock the suction created in the reservoir by the previous expansion of the feeder. It is apparent then, that when the operator pushes first one treadle 9 and then the other, the suction within the reservoir will be progressively increased so as to cause the same to collapse against the force of the springs 18. The tension of the springs 18 is so adjusted, that the amount of suction required to initiate the movement of the leaf 15 toward the leaf 16, is only sufficient to operate the pneumatic action of the piano so as to produce medium tone effects.

It has been found that with the type of reservoir heretofore employed, the amount of resistance encountered by the operator in moving the treadles 9, remains about the same until the reservoir is completely collapsed, at which time the resistance to movement of the treadles increases very greatly, owing to the fact that the movable leaf 16 can move no farther. It is also well known that when operating a player piano of the type to which my invention relates, the expression with which a piece is played, depends almost entirely upon the operation of

the treadles 9. It therefore follows that when the resistance to the movement of the treadles increases suddenly, following the complete collapse of the reservoir, the operator of the piano is unable to produce the variation in the pressure for playing the notes, without using undue effort in moving the foot treadles.

As previously set forth, it is one of the objects of the present invention to provide an improved bellows, or reservoir, which is adapted to produce a wide range of pressure intensities without opposing undue resistance to the movement of the treadles operating the feeders. To this end, I construct the movable leaf 16 of the reservoir of a number of laminations 16^a, and in addition, provide a bumper 25 projecting outwardly from the face of the stationary leaf 15. When the reservoir is partially collapsed by operation of the pump, the movable leaf 16 strikes the bumper 25, thereby arresting the movement of the leaf 16. The creation of additional suction within the reservoir, after the leaf 16 has engaged the bumper 25, causes the leaf 16 to yield toward the leaf 15, owing to its flexible nature. The flexing of the leaf 16 permits a high pressure to be built up and maintained without a sudden increase in the resistance to movement of the treadles, as would follow if the leaf 16 were entirely rigid and unyielding. With my improved reservoir functioning as described, the operator can play the notes with a wide range of pressure intensities, without ever encountering any great resistance to movement of the treadles, as when using completely collapsible reservoirs of the type previously constructed.

Referring now to Figs. 1 and 4, the suction produced by the reservoir is transmitted through a tube 26 to the wind chest 27 by means of a passage 28 provided in the action block 29. A channel board 30 forms one side of the wind chest 27 and has secured thereto two sets of pneumatic units for operating the player action. As previously set forth, my invention contemplates an improved construction of the pneumatic units, and as all these units are identical in construction, only one will now be described in detail, with reference to Figs. 4 to 9 inclusive.

Each pneumatic unit provides a chamber 31 which is connected to the wind chest 27 through a channel 32 in the board 30, as shown in Fig. 6. The top of the chamber 31 is provided with an opening, the rim of which is surrounded by a metallic annular valve seat 33, upon which is seated a valve member 34. As best shown in Fig. 8, the valve member 34 is provided with a downwardly extending stem 34^a, upon which closely fits a metallic guide 35, which as best

shown in Fig. 9, is star-shaped in form, with its extremities adapted to fit closely within the valve seat 33. The guide 35 serves to hold a leather cover 36 loosely against the 5 underside of a washer 37, that portion of the cover 36 beyond the washer 37 being glued to the valve. Only the unglued portion of the leather is in contact with the edge of the seat 33, so that the two free layers of leather 10 serve to act as a pad for the seating of the valve, and at the same time, render it air tight when high pressures are developed, as will hereinafter be described.

The top of the valve 34 is covered with a 15 leather washer 38, which, when the valve 34 is raised from its lower seat, is adapted to engage an upper seat 39 having an opening 40 therein, as best shown in Fig. 5. When the valve 34 is in its lower position, as shown, 20 the opening 40 connects the interior of the power pneumatic 41 with the atmosphere, so that the latter is maintained in an expanded condition. The movable leaf 42 of the power pneumatic is provided with a finger 43, 25 which, as best shown in Figs. 4 and 5, is cupped-shape in form, with a slot extending therethrough for receiving the pneumatic wire 44. Nuts 45 are provided on the wire 44 for adjusting the same on the finger 43, 30 and the upper end of the wire 44 is connected to a striking lever 46. The lever 46 is provided with a capstan or stud 47 which, as best shown in Fig. 1, is adapted to engage 35 the wippen 48 of the piano action, which is illustrated as being of the usual form. A limit or stop, 49 is provided above the striking member 46 to limit upward movement of the latter, so that the power pneumatic 41 will move the wippen 48 exactly the same 40 amount that it is moved by the key 50 of the piano when the pneumatic is actuated, as will now be described.

A flexible diaphragm 51 divides the chamber 31 into two parts, and that portion of the 45 chamber below the diaphragm 51 is connected to a vertical duct 52 in the channel board 30 by a horizontal passage 53. The diaphragm is normally maintained in the position shown by reason of the suction in the 50 chamber 31 through the channel 32 and through the "bleeder" vent 57 extending from the duct 52, the valve 34 then being tightly held against the seat 33 by atmospheric pressure on top of the valve 34. The 55 duct 52 is connected by a tube 54 to the tracker bar 55 of the piano, the opening at the end of the tube 54 being normally closed by the music sheet 56. When, however, an 60 opening in the sheet 56 registers with the opening at the end of the tube 54, atmospheric pressure will be admitted through the duct 52 into the space below the diaphragm 51. This pressure will overcome the suction 65 through the vent 57 and will cause the diaphragm 51 to be raised, thus lifting the valve

34 away from the seat 33 into engagement with the upper seat 39. The opening 40 is thus closed, and suction is exerted on the inside of the power pneumatic 41, which causes it to collapse. The resulting upward movement of the leaf 42 is transmitted to the wippen 48 through the wire 44, and the striking member 46, thus causing the note to be struck. As soon as the movement of the music sheet 70 covers the opening in the tube 54, the diaphragm 51 falls, the valve 34 closes, and the pneumatic 41 is again expanded. 75

Each pneumatic unit is secured to the channel board 30 by means of screws 58, and in order to remove a unit from the piano it 80 is only necessary to remove the screws 58 and to slip the wire 44 out of the slot in the cupped-shape finger 43. The units are interchangeable, and being arranged in only two tiers, occupy a minimum amount of space 85 within the piano. For this reason the diaphragm 51, together with its float 51^a, is made oval in form, as shown in Fig. 7, thus materially reducing the width of my improved unit as compared to previous unit 90 pneumatics employing a circular diaphragm.

As previously pointed out, the valve 34 of each pneumatic unit is adapted to seat very tightly on the annular valve seat 33 by reason of the fact that the rim of the seat 33 95 engages the unglued portion of the cover 36. The fact that there is always a very small clearance between the unglued portion of the cover 36 and the washer 37 insures that when the valve 34 is seated by suction in the chamber 31, the layers of leather will compress slightly and provide a substantially air tight closure for the chamber. Obviously, the greater the suction to which the 100 valve is subjected, the more tightly it will be seated, so that the type of valve described herein is particularly adapted for use in connection with my improved air reservoir.

As previously pointed out, the provision of the flexible leaf 16 in my reservoir permits a 105 strong suction to be created without the exertion of undue effort on the part of the operator to move the foot treadles, and in order that the suction be maintained, it is most essential that the valves in the pneumatic units be air tight. By using a tight seating valve in connection with a suction creating device which can be operated without undue effort, I am able to employ and maintain extremely high pressures for operating the pneumatic player action. As a result, the pneumatic units can be reduced in size 110 as compared to those previously employed, which permits the very compact arrangement of the pneumatics in two tiers. For the same reasons, the proportions of the entire pumping device can be reduced, which results in a smaller and more compact arrangement of the entire instrument. 115

From the foregoing then, it is apparent 120

that by my invention I have provided an improved suction creating mechanism that is particularly adapted for use in connection with an improved form of pneumatic unit, whereby the playing qualities of the instrument are bettered and its ease of operation greatly increased.

I claim:

1. In a player for musical instruments, the combination with a valve mechanism for controlling a pneumatic player action, and a suction creating device, of a collapsible reservoir adapted to be exhausted by the operation of said suction creating device, said reservoir comprising a substantially rigid leaf and a movable leaf of material having marked resiliency as compared to said rigid leaf.
2. In a player for musical instruments, a collapsible air reservoir comprising a substantially rigid leaf, a movable leaf of material having marked resiliency as compared to said rigid leaf, and means for partially limiting the movement of said resilient leaf in the direction of said rigid leaf when the reservoir has collapsed a predetermined amount.
3. In a player for musical instruments, a collapsible air reservoir comprising a substantially rigid leaf, a movable leaf of material having marked resiliency as compared to said rigid leaf, and a stop for limiting the movement of a portion of said resilient leaf

when the reservoir has collapsed a predetermined amount, whereupon the remainder of said resilient leaf is adapted to yield in the direction of said rigid leaf.

4. In a player for musical instruments, a collapsible air reservoir comprising a substantially rigid leaf, a movable leaf of material having marked resiliency as compared to said rigid leaf, a spring for holding said leaves apart, and means for partially arresting the movement of said resilient leaf after it has moved a predetermined amount against the force of said spring, whereupon the said movable leaf is adapted to yield further by reason of its resilient nature.

5. In a player for musical instruments, the combination with a valve mechanism for controlling a pneumatic player action, a suction creating device, of a collapsible reservoir adapted to be exhausted by the operation of said device, said reservoir comprising a substantially rigid leaf, a movable leaf of material having marked resiliency as compared to said rigid leaf, and means for partially limiting the movement of said resilient leaf after said reservoir has been collapsed a predetermined amount by said suction creating device, whereupon said movable leaf is adapted to yield toward said rigid leaf in response to further operations of said suction creating device.

THEODORE P. BROWN.
